UNITED STATES PATENT OFFICE.

CLARENCE F. ADAMS, OF DAYTON, OHIO.

GAS-MANUFACTURING MACHINE.

Application filed January 11, 1922. Serial No. 528,546.

This invention relates to improvements in gas manufacturing machines in general, and more especially to that type of machine used for producing hydrogen gas by chemical process.

The objects of this proposed invention are, first, to provide a container in the form of a metal or wooden tank, in which the chemical reagents may be mixed and the evolution of gas suitably controlled; second, to provide a machine of extremely light weight conveniently arranged for transportation purposes and of great capacity, thereby providing a machine of great value for military purposes; third, to reduce the element of danger and risk to those operating a machine of this character of being burned, scalded, or mangled through explosions of chemicals now used in such machines; fourth, to make possible a single unit machine self-contained, easily operable by a single person.

Referring more particularly to the construction and mechanism described in the specification and illustrated in the drawings:

Fig. 1 is a vertical section through the combined mixing and generating tank, showing the agitator blades and gas outlet screen, the power plant, the gas condenser and drier, water cooler, water circulating pumps, system, cooling fan, driving mechanism, and the sludge valve at the bottom of the generator tank.

Fig. 1^a is a front elevation of the condenser and cooler showing the fan in dotted lines.

Fig. 2 is a plan view of the entire mechanism, showing the location of the power plant, main drive shaftings with bearings, clutches, and controls; agitator drive; solid reagent grinder and feed drive, reagent feed door, separator drum, gas condenser and drier, water cooler, cooling fan, water pumps and circulating system.

Fig. 3 is a view in elevation partly in section of the solid feed grinding mechanism.

Fig. 4 is an end view of the condenser and drier, showing water spray tubes, gas inlet and outlet tubes, gas chamber partitions, gas swirling fixtures, gauge glasses, drain plugs, water outlet connections, and gas and water circulating system.

Fig. 4^a is a longitudinal section of one

of the tubes showing the spiral baffles or swirlers.

Fig. 5 is a side elevation of the gas condenser and drier with an air cooling fan mounted in connection therewith. This figure also shows a side view of the gas chamber compartments, water inlet and outlet.

Fig. 6 is a graphic illustration in sectional elevation of the agitator of the action of the agitator on the liquid solution and the gas as it rises from the solution, the distribution of solid material as it passes through the grinder into the generating tank and the breaking up of the gas bubbles as they leave the generator.

Fig. 7 is a plan view of the device showing the location of the clutch and power controls by which a single operator may control the whole plant from one position.

Fig. 8 is a view in vertical section through the sludge valve showing the manner in which its stem is carried through one side of the foundation beam and operated by a crank or hand wheel from a convenient position.

Referring to Fig. 1, A represents the foundation or framework upon which the entire machine is assembled and mounted. It may be constructed of channel iron, steel tubing, or any other suitable material, or the framework of a truck or trailer. B is a tank constructed of sheet metal, boiler plate, wood or other suitable material and serves as a container in which the reagents may be mixed. This tank B contains an agitator C which is used to facilitate thorough mixing of the reagents, to keep them in solution during the operation, to beat down and break into small particles the gas bubbles that are generated through chemical action in the solution, and to aid in the thorough distribution of the fine particles of the reagent material fed through the grinder D. The bottom of tank B is sloped towards the center in order to more easily draw off the sludge through the valve E and also provide a greater depth for the solution at its center than at other points, it being found through experiment that a greater efficiency is thereby attained in the holding of temperatures and the evolution of gas through the chemical action of the reagents. F is a screen made of wire cloth through which the gas must pass in leaving the generating tank. It may be made in the shape of a

cone, cylinder or disc, its function being to further break up the gas bubbles after they have been pounded by the upper blades of the agitator C. G is a drum, containing baffle plates against which the gas bubbles must strike before being released to continue their travel to the condenser H. This baffling of the gas bubbles results in their giving up moisture carried from the solution from which they have been generated. J is a drain pipe connected at its upper end to G and at its lower end with the generating tank B.

This pipe is provided with a valve K to release any accumulation of moisture from the drum G, allowing it to drain back to the tank B. The condenser H and the radiator I are of the tubular type and may be made up of any suitable material that will resist corrosion and conduct heat efficiently. Gas is caused to flow from the generating tank B, due to an internal pressure created therein by the action of the reagents and in its passage from the tank is taken through the drum G, the condenser H, and then released to a suitable container, such as a balloon or tank. Passage of the gas through the condenser and the specific function of this part of the apparatus is further explained in Fig. 4 to follow. Mounted on shaft L is a cooling fan M interposed between condenser H and radiator I. The function of this fan M is to draw cool air through the radiator and force the air on through the condenser, keeping an airstream flowing through between the tubes of both the condenser and cooler while the plant is in operation. This airstream created and maintained by the fan M not only extracts heat from the water of the radiator and the gas flowing through the condenser, but causes a considerable amount of the extracted heat to be impinged on the outside surface of the tank B, thus aiding in maintaining the temperature of the solution in the tank at a point which will provide for the highest thermal efficiency in the generation of the gases. The shaft L carries two sprockets N and O, sprocket N being driven by a chain from a sprocket V on an overhead shaft Q. Sprocket O is a driving sprocket transmitting motion through a chain to sprocket R on water circulating pump shaft S. Two centrifugal water pumps P—P' are mounted on shaft S and maintain a circulation of water through condenser H and radiator I. This circulation may be regulated by manipulating the clutch T, cutting off and putting on power to shaft L. This manipulation of the clutch T will also affect the airstream passing through the condenser and cooler and in conjunction with the circulating water in the condenser and radiator affect the temperature of the delivered gas and also the temperature of the gas and solution inside the

generating tank. The sprocket W on overhead shaft Q is driven by a chain from sprocket X connected to the power plant p p through a flexible connection such as a clutch.

Referring more particularly to Fig. 2, the overhead shaft Q carries a gear D² that meshes with a gear E², which is connected through the shaft I² with a set of gears F² which drive the agitator and the shaft G² connected through a clutch H² and a set of gears, not shown in this figure, to solid reagent grinder D.

A trap door Y is hinged at K² and K³ on the upper end of tank B, and when closed is held in place by spring Z clamped by a pin passing over spring Z and through two lugs M² on opposite sides of spring Z. The aperture normally closed by the door Y may be used as an entrance to tank B for the purpose of repairing the agitator or other parts within the tank B, but is usually used for dumping into the tank such reagents as caustic soda, lime, etc., in the case of hydrogen manufacture. Control arms B² and B³ are attached to bell cranks A² and A³. The opposite end of bell crank A² connects through a bar N² to clutch T. The bell crank A² enables the operator of the grinder D to manipulate clutch T by actuating bar B². The clutch between the sprocket wheel X and the source of power of the plant is similarly controlled by the operator of the grinder D by a similar arrangement on opposite sides of grinder D.

Fig. 3 is a sectional view of the grinder D referred to in the description of Figs. 1 and 2, and consists of a vertical shaft M³ on the lower end of which is attached a beveled disc O², the upper surface of which is grooved radially from the center of the circumference. On the upper end of shaft M³ is fitted a gear P² that meshes with a gear P³ on one end of shaft G². The gear P² is loosely fitted to shaft M³, but contains a slot in which slides a key R² which is fitted into shaft M³. This arrangement makes it possible to drive shaft M³ through gears P², but at the same time enables a reciprocating motion of shaft M³ through gear P². At R³ on shaft M³ is a shoulder that enables the weight of shaft M³ and its accessories to be supported by a bearing S² which is fitted within a bushing S³ threaded as shown at T². By turning bushing S³ to the right or left, shaft M³ is raised and lowered. The lower end of shaft M³ is mounted in a bushing T³ which is fitted in a spider T⁴. Riding on shaft M³ is a plug V² which is reciprocated by operating lever V³ connected to plug V² by a link V⁴. The body of the grinder D is made in the shape of a cylinder, into the upper end of which is fitted a casting W² threaded in the center to receive the bushing or plugs S³ and at the lower end of which is fitted the spider

T⁴ carrying the bushing T³. On the inside and slightly above the bottom of grinder D is fitted a ring W³; beveled on both faces toward its center and having its lower face 5 grooved in a similar manner to the upper face of O². Above the ring W³ is fitted a cone hopper X², the apex of which is provided with a suitable opening to receive the shaft M² and about three-fourths of the plug 10 V². The body of the grinder D is further provided with a flange ring X³ to enable the mounting of the grinder on the tank B. Clutch X⁴ provides a means of connecting and disconnecting the shaft Q with the 15 power plant.

The operation of this part of the plant is as follows: By pushing down on the lever V³ the apex of the cone hopper is closed by the plug V². Solid reagent material is then introduced into the hopper through either a hole provided in the casting W² or a hole through the side of the tank above the hopper; or through both preferably as shown, a covered hole —h— in the 20 wall of the hopper is provided (see Fig. 3). The space between the grinder parts of the mechanism O² and W³ is then adjusted by turning the screw plug S³; which operation, as previously mentioned, raises or lowers 25 the shaft M² and consequently the grinder disc O². For silicious material when hydrogen gas is being generated, it has been found through experiment that the grinder should be adjusted to grind the material as 30 finely as possible. To feed the solid reagent material to the tank B; assuming the plant now in motion and the grinder shaft turning, the plug V² is slightly opened and moved up and down until the desired 35 amount of material has been fed from the hopper X² to the grinder when the plug is brought back to a closed position and secured by the dog X⁴, engaging in a notch on lever arm V³ at X⁵. As there may be a 40 considerable pressure generated on the inside of tank B when the gas is being manufactured, the plug V² should always be closed except when feeding material from the hopper to the grinder to prevent gas 45 from escaping out through this part of the plant's equipment. Should the vapor arising from the inside of the tank B cause a chunking of the material above the grinder disc O², the disc is lowered by adjusting 50 threaded bushing S⁴, allowing the chunks to fall between the grinder ring W³ and the disc O². The disc is then gradually raised through the adjustment bushing S³ and the 55 chunks ground to a powder and fed to the tank B.

In using the grinder just described in a series of tests on a working model of plant as described, it is found that in feeding silicious material to a solution of caustic 60 soda to generate hydrogen gas, the operator

of the grinder may easily control the temperature inside the tank B by watching a thermometer placed in a convenient position, adapted to indicate the temperature inside the tank B, and feeding silicious material in greater or less quantity as needed to maintain this temperature at a point which will produce the highest efficiency in the evolution of gas. The internal pressure of the tank B is also regulated and kept below the point of danger by regulating the feed of silicious material through said grinder. The combination of the hopper X², plug V² with its control lever V³, the grinder disc O², and grinder ring W³ and the 70 adjustment bushing S³ enables a positive feed of silicious material at all times and thoroughly protects the operator from being burned or scalded by a caustic spray thrown off from the generating tank B up through 75 the grinder and feed mechanism D.

Referring to Fig. 4, the condenser consists in a number of tubes C⁴; with boxes or drums C⁵ and C⁶ attached to the ends. The condenser is divided into two parts as far 80 as the flow of gas is concerned, by dividing the lower box or drum C⁵ into two compartments by means of a partition D⁶.

The upper box or drum C⁵ of the condenser is also divided into two compartments, but the partition D⁷ is located in a plane at right angles to the partition D⁶ in the lower tank or drum. Below partition D⁷ and just above the upper ends of the tubes of the condenser is located a system 90 of pipes D⁸ which are connected with the water cooling system of the condenser and radiator. These are so placed in reference to each other and perforated with small apertures so that when water under pressure is pumped into them a fine spray of water will be forced against all of the tubes of the condenser, and also the lower surface of the compartment D⁹ as indicated at the top of Figure 4 below the pipes D⁸. Into the upper compartment or tank or drum C⁵ are placed long, narrow, and shallow pans D¹⁰ to contain the drying material, such as unslaked lime. In the bottom end 95 of the tube in the inner half of the condenser E⁵ or the half next to the tank B is placed a swirling device made of light sheet metal or any material not subject to corrosion. The object of this device is to set the gas into a swirling motion as it passes through 100 the tube, it being found by experiment that this gives the gas a good contact with the inner walls of the tube and increases materially the cooling and condensing qualities 105 of the condenser.

Referring to Fig. 5, on one end of the upper compartment of the upper drum or tank C⁵ is hinged or attached in any convenient manner a small door H⁸, covering a hand hole through which the pans D¹⁰ 110

are placed in or removed from said compartment. This door is provided with a gasket to insure a tight joint when closed. Each compartment of the lower drum or tank C⁶ is provided with a drum plug G⁶ and G⁷ and nipples G⁵ which are a part of the manifold I⁶, which is connected by the regulating valve G⁹ to the pump P. From pump P extends a pipe F⁶ to the upper compartment 10 of the radiator I. A nipple F⁸ is connected in the lower compartment of the radiator I and leads through the regulating valve G⁹ to the pump P'. From pump P' a pipe F⁷ connects with a manifold L⁷, which is a part 15 of the pipe D⁸. Gauges H⁶ and H⁷ are attached to the compartments of the lower drum or tank C⁶ and serve to indicate the amount of water contained therein.

The action of the condensing and cooling apparatus as described in Figs. 4 and 5 is as follows: Gas is led from tank B through drum G to a pasageway D⁶ which leads to the lower compartment of the condenser next to tank B. Gas is then forced 20 up through the swirlers in the tubes C⁴ as indicated in Fig. 4^a, one of which is placed in the bottom of each tube of the inner half of the condenser E⁵. The gas being thus set in a swirling motion allows all of the gas 25 particles to impinge against the walls of the tube and give up heat and any solid substances being carried. The released heat is then partly carried away by water which is trickling down the inner walls of the tubes 30 and partially by the air stream forced between and around the outside walls of the tubes. Solid particles are prevented from sticking to the inner walls of the tubes by being washed down to the lower tank or 35 drum of the condenser by the same water, in the tubes, that absorbs heat from the gas as it passes upward to meet the water spray from the pipes D⁸. The water in passing down through the tubes increases in temperature as it falls towards the bottom. 40 Thus the incoming gas meets the warmer water first, giving up practically all solid matter near the bottom of the tube, and as the gas rises and meets cooler water the loss 45 of heat by the gas particles increases.

When the gas reaches the compartment C⁵, it is subjected to a thorough drenching and pounding from the water spray system D⁸ and is then forced down through the 50 tubes of the outer half of the condenser E¹⁰ to the lower compartment of this half and is then conveyed through a passageway D¹¹ to the drying compartment in which it passes over pans D¹⁰ containing the drying 55 material and is then released through a pipe or hose D¹² to a suitable container. The gas in passing down through the tubes of the outer half of the condenser E¹⁰ is in contact with the water spray throughout its 60 travel to the outer compartment of the lower 65

tank or drum C⁶. The water in passing through the tubes of this part of the condenser not only assists the gas in its downward travel, but also serves to further extract heat from said gas.

The circulating water is primarily cooled by the radiator I, but gives up a certain amount of heat that it absorbs from the gas as it passes through the condenser H due to the air stream from the cooling fan. 70 Water is forced from the bottom of the radiator I through pump P' up to the water spray system D⁸ where it is divided into a fine spray falling down through the tubing of the condenser to the two compartments 80 of the lower drum or tank C⁶ and is extracted therefrom through the pump P and forced through pipe F⁶ to the upper part of the radiator I. As cool water is taken from the bottom of the radiator and forced 85 to the upper part of the condenser and warm or hot water is taken from the bottom part of the condenser and forced to the upper part of the radiator, the circulation established is in a direction harmonious to 90 the heat exchange effect. A suitable hose or pipe may be provided to convey the water between the pumps and the radiator and condenser. The nipples G⁵ and F⁸ are extended a sufficient distance up into the lower 95 compartments of the condenser and radiator to prevent solid material from being forced through the water circulating system.

Referring more particularly to Fig. 6, which is a graphic illustration of the apparatus and action of the gases within the generator and mixing tank B and drum C, the agitator and mixer is made up of two principal parts; first, the framework including a propeller, revolved in such a direction 100 that it will beat down the bubbles rising from the solution, and the two vertical arms S¹⁰ and S¹¹, and the horizontal arm S¹², which has attached to it two scraper plates T¹⁰ and T¹¹. These two scraper plates drag 105 three or four links W¹⁰ of medium sized chain, the hollow shaft U¹¹ being connected with arm C and gear U¹² and the horizontal propeller arm U¹⁰. The second part consists of the shaft V⁷ leading from the bearing V⁸ in the bottom of the tank through 110 shaft U¹¹ and connecting with gear V⁹ the propeller arms V¹² which are set to propel the liquid in an upward direction. The gear I⁹ attached to the shaft I² being in mesh 115 with both gears V⁹ and U¹² causes the two parts of the agitator to be driven in opposite directions.

The solution having been placed in tank B through a pipe or hose, the agitator is set 120 in motion and the solid reagents are fed through the grinder D. In accordance with a known process such solution referred to consists of slaked lime, and caustic soda. 125 Clearly the drying material employed in the 130

pans D^{10} when expended can be included. As the material is released from the grinder it is thrown out in the shape of a cone, the base of which is caught by the upper arms or propellers of the agitators, carried around through the entire upper part of the tank and forced down to the solution where chemical action takes place generating the gas. The reagents are kept effectively only in solution and brought together by controlling the temperature inside the tank B and by regulating the speed of rotation of the agitator blades, the lower ones constantly revolving in the solution. Solid material is prevented from accumulating in the bottom of the tank by the action of the scrapers T^{10} and T^{11} and the dragging of the chain links W^{10} . As the bubbles of gas rise from the solution, their release being aided by the upward propulsion of the propelling arm U^{10} , the bubbles come into contact with the propelling arms of that part of the agitator which is normally above the solution and are practically disrupted, thus creating smaller gas bubbles and releasing a great amount of moisture. The mixture is then forced through the outlet screen F , where it is further broken up before entering the drum G . In passing through the drum G the gas is caused to impinge against a series of baffle plates W^{12} which not only aids in further breaking up the mixture, but causes a great deal of moisture and heat to be given up before being released to the condenser. The speed at which the agitator blades must be revolved and the amount of solid material to be fed through the grinder D while gas is being manufactured depends largely on the materials used above, the kind of gas to be manufactured, and the surrounding atmosphere. Only in this way can the proper chemical combination of slaked lime and caustic soda be effected to produce calcium silicate, and in the sludge, sodium hydrate. As stated above the important thing is the regulation of temperature and of pressure produced by means of controlling the feed of the reagent material.

Referring to Fig. 8, which is a view in section through sludge valve E , said valve is provided with a flange X^{10} for securely attaching by means of bolts or screws to bottom center of tank B . The valve gate X has a beveled seat facing outwardly from the chamber of the valve. This arrangement is provided to prevent the lodging and adhering of solid material to either the valve seat or the valve face when the valve is opened to drain the sludge from tank B . The valve gate is controlled by a partially threaded stem X^{12} which extends through to the outside of the frame V^{10} and terminates in a hand wheel or crank V^{11} for convenience in operation. The threaded portion of the valve stem X^{12} extends through

a block Y^{12} threaded to receive it. This block is part of a shield or cover Y^{14} , which insures the deflection of the sludge in a downward direction and serves to protect the valve gate X . The object of the sludge valve E is to provide what amounts to being a continuous process for the production of hydrogen gas. This follows in the first place by virtue of the hopper control V^2 and secondly the base structure and agitator arrangements of the chemical combination tank B .

It will be seen that by the proposed arrangement of clutch controls B^2 and B^3 and ignition and gas or electrical control C^2 near and convenient to the grinder, the single operator may be located at grinder D and control the operation of the entire plant.

What is claimed is:

1. In a gas manufacturing apparatus, a receiving container for chemical solid reagents, said container being provided with a valve regulated hopper, a grinder ring mounted in said container below said hopper, and a grinder disc adapted to rotate against the lower face of said grinder ring for the purpose of grinding said solids, said grinder ring having its upper and lower inner faces beveled inwardly, and said grinder disc having its upper face beveled to correspond with the lower face of said grinder ring, a gas generator provided with a mixing chamber and controllable means for discharging the product of the grinding apparatus directly into the mixing chamber.

2. In a gas manufacturing apparatus, a receiving container for chemical solid reagents, said container being provided with a valve regulated hopper, a grinder ring mounted in said container below said hopper, and a grinder disc adapted to rotate against the lower face of said grinder ring for the purpose of grinding said solids, said grinder ring having its upper and lower inner faces beveled inwardly, and said grinder disc having its upper face beveled to correspond with the lower face of said grinder ring, the upper face of said disc and the lower beveled face of said grinder disc having corresponding radial grooves therein, a gas generator provided with a mixing chamber and controllable means for discharging the product of the grinding apparatus directly into the mixing chamber.

3. In a gas manufacturing apparatus, a receiving container for chemical solid reagents, said container being provided with a valve regulated hopper, a grinder ring mounted in said container below said hopper, and a grinder disc adapted to rotate against the lower face of said grinder ring for the purpose of grinding said solids, said grinder ring having its upper and lower inner faces

beveled inwardly, and said grinder disc having its upper face beveled to correspond with the lower face of said grinder ring, the upper face of said disc and the lower beveled face of said grinder disc having corresponding radial grooves therein, a reciprocating conical valve for closing the opening in said hopper, said valve being adapted to be reciprocated by a plurality 10 of link levers, one of said levers being provided with notches to receive a stop pawl, a gas generator provided with a mixing chamber and controllable means for discharging the product of the grinding apparatus directly into the mixing chamber.

4. In a gas manufacturing apparatus, a container for chemical solid reagents, means within said container for grinding said solids, said means comprising a grinder ring 20 and a grinder disc adapted to be rotated against said ring, said disc being mounted on a vertically extending rotating shaft in fixed relation laterally and slidably adjustable relation vertically with respect to said shaft, said shaft being provided at the top plate of said container with an adjustable bushing adapted to engage a shoulder on said shaft, a gas generator provided with a mixing chamber and controllable means for discharging the product of the grinding apparatus directly into the mixing chamber.

5. In a gas manufacturing apparatus, a container for chemical solid reagents, means within said container for grinding said solids, said means comprising a grinder ring and a grinder disc adapted to be rotated against said ring, said disc being mounted on a vertically extending rotating shaft in fixed relation laterally and slidably adjustable relation vertically with respect to said shaft, said shaft being provided at the top plate of said container with an adjustable bushing adapted to engage a shoulder on said shaft, said shaft being provided at its upper end with a beveled gear adapted to mesh with a beveled gear on the shaft of a prime mover, a gas generator provided with a mixing chamber and controllable means for discharging the product of the grinding apparatus directly into the mixing chamber.

6. In a gas manufacturing apparatus, a container for chemical solid reagents, means

within said container for grinding said solids, said means comprising a grinder ring and a grinder disc adapted to be rotated against said ring, said disc being mounted on a vertically extending rotating shaft in fixed relation laterally and slidably adjustable relation vertically with respect to said shaft, said shaft being provided at the top plate of said container with an adjustable bushing adapted to engage a shoulder on said shaft, said shaft being provided at its upper end with a beveled gear adapted to mesh with a beveled gear on the shaft of a prime mover, and a hand-operated clutch mechanism for engaging and disengaging said prime mover from said grinder disc shaft, a gas generator provided with a mixing chamber and controllable means for discharging the product of the grinding apparatus directly into the mixing chamber.

7. In a gas manufacturing apparatus, a gas generator including a mixing chamber, a vertically extending hollow shaft mounted in said chamber, a solid shaft mounted free to rotate within said hollow shaft, a plurality of propelling arms mounted on said hollow shaft adapted to exert a downward pressure when rotated, and a plurality of propelling arms mounted on said solid shaft, a plurality of said last named arms being adapted to exert a downward pressure and one of said arms being adapted to exert an upward pressure when rotated.

8. In a gas manufacturing apparatus, a gas generator including a mixing chamber, a vertically extending hollow shaft mounted in said chamber, a solid shaft mounted free to rotate within said hollow shaft, a plurality of propelling arms mounted on said hollow shaft adapted to exert a downward pressure when rotated, a plurality of propelling arms mounted on said solid shaft, a plurality of said last named arms being adapted to exert a downward pressure and one of said arms being adapted to exert an upward pressure when rotated, a gas outlet pipe at the top of said mixing chamber, said pipe being provided with internal baffling means, and a wire mesh strainer located at the entrance to said pipe.

In testimony whereof I affix my signature.
CLARENCE F. ADAMS.
